UNITED STATES PATENT OFFICE

PETER S. DUNN, OF NEW HAVEN, CONNECTICUT, ASSIGNOR TO SARGENT & COMPANY,
OF NEW HAVEN, CONNECTICUT

LATCH

Application filed November 8, 1928. Serial No. 317,949.

This invention relates to a latch, and more especially to a latch provided with a readily removable latch bolt and retracting mechanism.

It is, in general, an object of the invention to bring about a simplified form of latch having but few parts, and wherein the parts may be readily assembled and disassembled without the use of tools.

Another object of the invention is to bring about an arrangement of a latch and latch retracting lever wherein these parts may be mounted and secured in a latch case without the use of rivets, screws, or other fastening means.

A further object of the invention is to bring about a latch of the above character in which it is impossible for the parts to be accidentally disassembled from the case or rendered inoperative during the normal operation of the lock.

To these and other ends, the invention consists in the novel features and combination of parts to be hereinafter described and claimed.

In the drawings,

Fig. 1 is a plan view of a latch, according to my invention;

Fig. 2 is a front elevation of the same;

Fig. 3 is a sectional view along line 3—3 of Fig. 1;

Fig. 4 is a view similar to Fig. 3, but showing the latch bolt retracted; and

Fig. 5 is a view similar to Fig. 3, but showing the parts in another position.

Referring to the drawings in which I have illustrated my invention by showing a preferred embodiment thereof, the reference numeral 10 indicates, in general, a hollow latch case having at one end thereof an opening 11, in which the head 12 of latch bolt 13 is received, and at the opposite end an opening 14 in which the stem 15 of bolt 13 is received. Mounted on stem 15 is a compression spring 16 having one end bearing against an inner surface of rear wall 17 of case 10, the opposite end of spring 16 bearing against head 12 and bringing about the protraction of the bolt. In order to retract the latch bolt 13, a lever 18 is provided pivotally mounted on case 10

and having an arm 19 received in a slot 20 in head 12.

Case 10 is provided with a pair of spaced integrally formed ears 21 and 22, having extending therebetween a substantially cylindrical pivot lug 23, which is received within a semi-cylindrical opening 24 in lever 18 and forms a pivotal connection between case 10 and lever 18. The arm 19 of lever 18 tapers downwardly and is of relatively less width at its lower end than opposite the opening 24, the lower end of arm 19 being provided with a rearwardly directed lug 25, which during the normal operation of the latch is received under a forwardly extending shoulder 26 at the rear end of the opening 20 in latch bolt 13. In order to limit the protraction of latch bolt 13, the rear wall 17 of case 10 is continued upwardly to a point 27 substantially opposite the upper edge of pivot lug 23, where it may be engaged by the handle 28 of lever 18, while the movement of lever 18 in retracting latch bolt 13 is limited by face 29 of lever 18, which engages face 30 of case 10. Laterally extending flanges 31 and 32 are provided for mounting the latch on a door or the like, while reference numeral 33 indicates a strike provided with a latch bolt-receiving opening 34.

The operation of the latch will be readily understood from the above description but may be briefly described as follows:

Figs. 2 and 3 show the latch with the bolt 13 fully protracted and the handle 28 resting against the upper edge 27 of wall 17, the bolt being forced into protracted position against the lower end of arm 19 by means of spring 16. Upon raising handle 28 into the position shown in dotted lines in Fig. 3, the retracting lever 18 is swung about pivot lug 23, the lower end of arm 19 engaging bolt 13 and forcing the latter rearwardly into the position shown in dotted lines. It is to be noted that in this position, the shoulder 25 is still engaged under shoulder 26 so that it is impossible to detach the retracting lever from the latch case. Thus, the latch bolt may be retracted and protracted without any danger of the operative parts being detached from the case.

In order to detach the latch bolt, spring and retracting lever from the case, the operation is as follows: The latch bolt is retracted by pressing on the nose 35 of latch bolt head 12 by means of a suitable instrument and forcing the latch bolt further into case 10 than the normal retracted position. When the bolt is retracted in this manner to the limit of the compressibility of spring 16, or at least to such a position that the shoulder 26 on bolt 13 clears shoulder 25 on lever 18, and the lug 23 clears the edges of opening 24 (Fig. 5), the lever may be withdrawn upwardly from the case 10 and separated therefrom, whereupon the latch bolt 13 and spring 16 may be withdrawn outwardly through opening 11. It is to be noted that the arm 19 of lever 18 is provided with a relatively flat face 36 which when the lever 18 is rotated into fully retracted position is spaced from the upper end 27 of wall 17. The clearance between face 36 and wall 17 permits the lever to be moved rearwardly from pivot lug 27 a considerable distance but the lever cannot be withdrawn from the case on account of the fact that shoulder 25 is still received under shoulder 26. However, when the bolt 13 is full retracted by a suitable tool applied to nose 35, the clearance between face 36 and wall 17 becomes still greater, and thus when shoulder 25 is clear of shoulder 26 the lever may be moved rearwardly from disengagement with pivot lug 23 and upwardly from bolt 13 to be separated from the latch case.

From the above description of the nature of my invention and the preferred embodiment thereof illustrated, it will be readily understood that the usual fastening means are entirely eliminated, and while the several parts of the latch may be readily disassembled when desired there is no danger of these parts becoming disarranged during the normal operation of the latch.

While I have shown a preferred embodiment of my invention, it is to be understood that the same is not to be limited to all the details shown but is capable of modification and variation within the spirit of the invention and the scope of the appended claims.

What I claim is:

1. In a latch, a casing, a latch bolt in said casing, and means pivotally mounted in the casing for retracting said latch bolt, said means including a part normally engaging a part of the latch bolt on the remote side thereof from the pivotal mounting and retained in the casing thereby.

2. In a latch, a casing, a latch bolt in said casing, means on said casing for retracting said latch bolt, and spring means for protracting the bolt, said retracting means including a part engaging the bolt to hold the retracting means in the casing during the normal protraction and retraction of the bolt, said part being disengageable from the

bolt by a movement of the bolt in the direction of retraction, beyond the normal retracted position of the bolt.

3. In a latch, a casing, a latch bolt in said casing, a pivoted lever mounted in the casing having a part engaging the latch bolt and adapted to retract the same, and means on said lever engaging a part of the latch bolt to retain the lever rigidly against movement out of the casing when the lever is separated from its pivotal mounting.

4. In a latch, a casing, a latch bolt mounted in said casing, and a retracting lever mounted in said casing, said latch bolt being provided with an opening and said lever being provided with an arm extending through said opening, and means on the lower end of said arm beyond the opening engaging said bolt to retain the lever in said latch casing.

5. In a latch, a casing, a latch bolt mounted in said casing and a retracting lever mounted in said casing, said latch bolt being provided with an opening and said lever being provided with an arm extending through said opening, and means on the lower end of said arm engaging said bolt to retain the lever against movement out of said latch casing, said means being disengageable from said bolt upon movement of the bolt in the direction of retraction beyond the normal retracted position of the bolt when fully retracted by the lever.

6. In a latch, a casing, a latch bolt mounted in said casing, a pair of ears on said casing, a pivot lug extending between said ears, a retracting lever insertable into said casing between said ears and provided with an opening in which said lug is received, said retracting lever having means thereon engaging said bolt to retract the same, and means on said retracting lever engaging said bolt to hold the retracting lever in said case.

7. In a latch, a casing, a latch bolt mounted in said casing, a pair of ears on said casing, a pivot lug extending between said ears, a retracting lever mounted between said ears and provided with an opening in which said lug is received, said retracting lever having means thereon engaging said bolt to retract the same, and means on said retracting lever engaging said bolt to hold the retracting lever in said case, said latch bolt being disengageable from the bolt upon movement of the bolt in the direction of retraction beyond the normal retracted position of the bolt.

8. In a latch, a casing, a latch bolt in said casing, said bolt being provided with an opening, a pivoted lever mounted in the casing, said lever having an arm extending through said opening, and a rearwardly directed shoulder on the lower end of said arm, said shoulder underlying a part of the bolt during the normal operation of the latter, said bolt being disengageable from said

shoulder upon movement of the bolt in the direction of retraction beyond the normal retracted position of the bolt.

9. In a latch, a casing, a latch bolt in said casing, a pivot lug in said casing, a retracting lever having an open faced recess in which the pivot lug may be received, and means on said retracting lever engaging said bolt to retract the same upon movement of the lever, and means independent of said lug for holding said lever in said casing, said last-named means being freely movable into position to disengage said lever.

10. In a latch, a casing, a latch bolt in said casing, a pivot lug formed on said casing, a retracting lever having an opening in which said lug is received, means on said retracting lever engaging said bolt to retract the same and means to limit the movement of the lever in retracting the bolt, said means comprising an outwardly extending face on said lever adjacent the opening and a part of said pivot lug with which said face comes in contact.

25 In witness whereof, I have hereunto set my hand this 29th day of October, 1928.

PETER S. DUNN.
